FILLING FEELER

George Cadorette, Hopedale, Mass., assignor to Draper Corporation, Hopedale, Mass., a corporation of Maine

Filed July 27, 1964, Ser. No. 385,207

2 Claims. (Cl. 139—281)

This invention relates to an improvement in a loom feeler mechanism and, more particularly, to that portion of said mechanism utilized to detect the presence and absence of filling on bobbins in looms of the fly shuttle type.

It is a general object of the invention to provide a new and improved feeler tip for filling feelers of the side-slipping type.

A further object is to provide a flexible feeler tip which will absorb a portion of the impact forces created during its intended function of detecting the presence and absence of filling on an operating bobbin.

It is a further object to provide a feeler tip that is readily slidable on a spent filling bobbin and yet yieldable in a direction to resist the initiation of false indication for filling replenishment when there is sufficient filling remaining for continued weaving on an operating bobbin.

A still further object is to provide a flexible feeler tip which through its ability to yield when making contact with the filling yarn on an operating bobbin, provides a cushioning effect that is less hazardous to the finer grades of filling than the known types of fixed feeler tips.

Further objects and advantages of the invention will become apparent from the following more detailed disclosure.

In looms of the fly shuttle type wherein said shuttle supports a filling carrying bobbin, it is common practice to utilize a filling feeler mechanism to detect the presence of filling on the active bobbin and to initiate replenishment of this bobbin upon indication of exhaustion of the filling supply wound thereon.

An example of a filling feeler mechanism which utilizes the side-slipping feature of the feeler element to actuate the means for bobbin replenishment similar to that of the instant invention is disclosed in United States Patent No. 1,599,806. This type of feeler mechanism is provided with a feeler case suitably mounted on a loom having a slideable and pivotal spring biased stem member extending outwardly and rearwardly therefrom. The outermost end of the stem member has a feeler tip affixed thereto which in a known manner is directly engaged by the filling supply in an operating shuttle.

Various forms of feeler tips are known and utilized for particular weaving conditions. On occasions the free end of the stem member itself is formed to serve as a feeler tip such as illustrated in the above-mentioned patent. Other common types of feeler tips are formed from solid blocks of plastic or the like and are fixedly attached, such as by rivets, to the free end of the stem member. The latter type of feeler tips usually have a configuration which provides line contact with the bobbin with which they are adapted to cooperate, that is to say, the contact surface of the tip is disposed at an angle perpendicular to the axis of the active bobbin.

As is well known in the art of weaving, contact between the feeler tip and an active bobbin which has sufficient filling thereon for continued weaving causes the stem member to be pushed forwardly, and as the loom lay moves rearwardly the spring means within the feeler case forces said stem outwardly to its initial position. During normal loom operation this motion is continuous causing the stem member to reciprocate and the feeler tip to contact the filling package in the same limited area many

2

times before exhausting or withdrawing the filling from this particular area. Repeated contact between the feeler tip and the same limited area on a filling package is known to have damaging effects on certain types of filling yarns such as crushing, pinching, and fraying to the extent of weakening and even the subsequent breakage thereof as it is withdrawn from the bobbin.

The improved feeler tip according to the instant invention mitigates these damaging effects to a filling package by providing a tip that is adapted to yield or flex when contacted by the filling package and yet will side slip readily to initiate filling replenishment upon contact with a bobbin on which the filling supply has become substantially exhausted.

Applicant's feeler tip is formed from flat and yieldable strip material such as spring steel with one end thereof being fixedly attached to the free or outer end of the rearwardly extending feeler stem. The form of the tip is such that it extends generally rearwardly in the form of a hook with the bight portion thereof being the surface adapted to cooperate with the filling bobbin. Contact between the filling package and feeler tip causes the latter to flex or yield slightly before forcing the stem member forwardly in the regular manner. This flexing or yielding of the feeler tip provides a cushioning effect at the time of impact with the filling package thereby providing a less severe feeler action to filling packages subject to the aforementioned conditions.

The invention will be described in detail by reference to specific embodiments thereof one of which is illustrated in the accompanying figures of drawing, wherein:

FIG. 1 is a plan view of a portion of a conventional loom shuttle box, shuttle, and filling bobbin with a feeler tip according to the invention and its associated components shown in filling detecting position;

FIG. 2 is a view similar to that of FIG. 1 but showing the position the feeler components are caused to assume when the filling package becomes substantially exhausted; and

FIG. 3 is a view in side elevation of the feeler mechanism shown in FIGS. 1 and 2.

Referring now to the drawings, FIGS. 1 and 2 show only so much of a conventional loom structure as is necessary for a full understanding of the instant invention. Included in the conventional loom structure shown in part is a shuttle box 10 into which a shuttle 11 carrying a bobbin 12 is receivable and from which it is picked in a manner well understood by those conversant with the weaving art. The bobbin 12 is provided with a filling package 13 wound thereon (FIG. 1) which during the process of weaving is withdrawn from said bobbin until substantially exhausted as depicted by the reserve filling bunch 14 shown in FIG. 2.

A filling feeler mechanism generally indicated by numeral 15 suitably mounted on the loom structure is adapted to cooperate with the bobbin and shuttle from which it derives an indication to permit continued weaving when sufficient filling is present on the active bobbin and to initiate replenishment of the same when said filling is nearly exhausted as shown in FIG. 2.

This mechanism comprises a casing 16, casing cover 17, and a filling feeler which includes a stem member 18 and a feeler tip 19. The stem member 18 protrudes from casing 16 through an opening 20 and has affixed to its free end the feeler tip according to the invention which is depicted by numeral 19. The feeler tip is fixedly attached to the outer end of the stem by any suitable means such as rivets 21.

The action of the stem member within the casing is well known to those familiar with the art and includes the usual coil spring 22 one end of which is attached to a laterally extending portion of the stem as at 23 with the other end

thereof being attached to a projection 24 disposed at the rear of the casing itself.

Spring 22 being assembled in the manner illustrated is continually urging the stem member rearwardly to its full feeling position and yet will permit said stem to pivot as shown in FIG. 2 to initiate filling replenishment.

The feeler tip 19 comprising the invention is formed from flat metallic spring material such as steel and it extends generally rearwardly from the outer end of the stem 18 for a portion of its length and thence angularly forwardly terminating a hook-like configuration. The hook portion or bight 25 of the feeler tip's configuration is adapted to make contact with the filling package and is so disposed as to make line contact with said package in a plane perpendicular to the axis of the bobbin and to said stem member.

In operation, the presence or absence of filling on the operating bobbin is detected when the feeler tip 19 enters an opening provided in the loom shuttle on the forward movement of the lay (not shown) when the shuttle is in a boxed position. If sufficient filling is present on the bobbin for continued weaving, the feeler tip on initial contact with the filling package will yield or flex slightly before the stem member is forced to move forwardly to expand coil spring 22. Relatively the spring tension of the feeler tip 19 is less than that of the coil spring 22 and provides said tip with a cushioning feeler action on the package prior to its forcing the stem forwardly in the conventional manner. Additionally, the hook configuration of the feeler tip is so disposed as to cause it to flex in a direction to resist sliding movement of the stem when making contact with the filling package thereby avoiding the possibility of false replenishment indications. The retraction of coil spring 22 urges the feeler tip and stem member to their normal extended position as the lay commences to move in a rearward direction.

When the filling yarn becomes depleted to the extent that replenishment is required, the feeler tip when making contact with the bobbin surface will readily slip sideways, as shown in FIG. 2, to the extent where the stem member 18 contacts and actuates a transmitter rod 25'. Movement of this transmitter rod in the direction of the indicating arrow 26 in FIGS. 1 and 2 actuates the filling replenishment mechanism.

While one embodiment of the invention has been dis-

closed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In a loom feeler mechanism having a feeler case with a slideable and pivotal stem member extending outwardly therefrom, a flexible feeler tip of flat metallic spring material having one end thereof affixed to the outer end of said stem, said tip being so disposed as to form a partial loop extending generally outwardly from said stem with the terminal portion thereof being directed angularly forwardly and generally toward said stem to form a bight portion outwardly of and adjacent said terminal portion, said bight portion being vertically disposed to provide perpendicular line contact with a filling bobbin with which it is adapted to cooperate to detect the presence and absence of filling yarn thereon.
2. For a loom feeler mechanism having a feeler case with a slideable and pivotal stem member extending therefrom, a flexible feeler tip of flat metallic spring material and having one end thereof affixed to the outer end of said stem in a manner whereby the width of the spring material extends in a vertical plane, said tip being so disposed as to extend generally outwardly from said stem with the terminal portion thereof being directed angularly forwardly and generally toward said stem to form a bight portion outwardly of and adjacent said terminal portion, said bight portion being vertically disposed to provide perpendicular line contact with a filling bobbin with which it is adapted to cooperate to detect the presence and absence of filling yarn thereon.
